Lois L. Sargent

Attorney

UNITED STATES PATENT OFFICE.

JAMES H. BOST, OF CHARLOTTE, NORTH CAROLINA.

METAL FRAME FOR WINDOW SCREENS.

Application filed December 29, 1925. Serial No. 78,204.

My invention relates to hollow sheet metal frames for holding screens, posters or pictures, or for any other purpose for which a small strong frame is required. It is an especial object of my invention to provide a metal frame screen that will frictionally hold screen wire in its roughened depressions, making it simple and practical to wire the frame without the wire slipping out until a hard cord of any suitable kind can be pressed into the center of the fold of the screen wire.

It is a further object of my invention to provide a frame which can be made up in long lengths and assembled by any small shop throughout the country, and to provide novel foundation angle members or corner pieces of different lengths each way and which may be cut to approximately match the size of the frame desired; and to assemble the metal screen frame in a facile and efficient manner.

I attain these and other objects of my invention by the device illustrated in the accompanying drawings, in which:

Figure 1 is a front plan view of my invention;

Fig. 2 is a section on line 2-2 of Fig. 1;

Fig. 3 is a perspective group view of the members forming the foundation angle or corner piece with portions of the longitudinal frame members that engage in said corner piece; and

Fig. 4 is a detail view showing the method of mounting the spring 13 in frame 1.

Like characters of reference designate like parts in each of the several views.

Referring to the accompanying drawings, I provide longitudinal and transverse frame members 1 having longitudinal depressions 2. I also provide inner foundation angle frame members or corner pieces 5, from which the frame members 1 telescope, as indicated in dotted lines at one of the corners of Fig. 1. Frame members 1 are provided with a beveled or mitered end 17 so as to meet diagonally at the corners. Frame members 1 are provided with approximately U-shaped recesses 3 and these recesses have opposite roughened surfaces 4 to frictionally engage the wire screen mesh 6, which is held in place by a suitable hard

cord 7, as shown in Fig. 2. I provide a plate 8 approximately L-shaped in cross section to engage the screen frame 1 and screen 6 and to conceal the cord 7, as illustrated in Fig. 2. Plate 8 is fastened to frame 1 in any suitable manner, preferably by hollow rivets or bolts, such as the members 19 and 20, shown in Fig. 2. Plate 8 is provided with a longitudinal depression 9 positioned opposite the corresponding longitudinal depression 2 of frame 1. Plate 8 is provided with a beveled edge 18 adapted to be engaged by the correspondingly flanged edge 10 of screen frame 1, as illustrated in section in Fig. 2. I provide an outer corner piece or angle cover 11 having depressions 12 corresponding in position and size with the depressions 2 and 9 of frame 1 and plate 8. The whole frame is held together by suitable rivets or double screws after the wire screen has been put in.

To permit of convenient insertion and removal of the screen, I provide springs 13 both mounted on one side of the screen frame, as shown in Fig. 1, the screen frame having a handle 15 attached to the opposite side thereof and having suitable handles 16 on the bottom portion of the screen. The spring 13 is mounted in apertures 14 in frame members 1.

The frame members may be made in long lengths and cut up to the desired length and assembled wherever desired. The corner pieces 5 constitute the foundation elements over which the frame members 1 are telescoped, the beveled or mitered edges 17 forming a tight and concealed joint. The outer corner piece 11 engages over the corners or angles of the screen frame. The wire screen mesh is readily fastened to the metal frame by inserting it in the U-shaped recess 3 and pressing a hard cord or any other suitable longitudinally extending fastening element into the recess or roughened edges 4 of the recess, as shown in Fig. 3, serving to frictionally grip the screen which the hard cord holds in place. The corner pieces and side frames are correspondingly grooved to permit of proper assembling of the parts.

The springs 13 both mounted on one side of the frame facilitate the insertion and

removal of the frame from a window, suitable handles 15 and 16 making it possible to manipulate the screen frame conveniently and advantageously.

- 5 The plate 8 which extends longitudinally of frame 1 and fastens the screen in place and conceals cord 7 is suitably fastened to the frame 1 by any suitable means but preferably by hollow rivets or bolts.
- 10 It is within the contemplation of my invention to provide metal rollers at the bottom for horizontally rolling the screens.

An important feature of my invention is the provision of the separate inside angle pieces, as this construction permits of the screen being built in various parts of the country and the frame members, which are stamped out in long lengths, cut to the proper length and fitted in the corner pieces in the manner illustrated in the drawings. This improvement is of importance, inasmuch as during the summer season the time lost in making special frames, finishing them and shipping them to distant points is one 25 of the most expensive features of the screen industry.

It is within the contemplation of my invention to alter the angle of the corner piece from a right angle should a modification of 30 shape be desirable for special purposes. It is also within the contemplation of my invention to make the frame of any suitable metal or other material which may be pressed or stamped to the desired shape.

35 It is also an important feature of my invention to provide the roughened surfaces of the U-shaped recess to permit of readily securing the wire mesh screen to the frames and holding it in place by means 40 of a hard or waterproof cord, which cord can be concealed by the plate 8 which is fastened to the main frame members.

My screen frame is normally about three 45 eighths of an inch thick by three quarters of an inch wide when finished, but may be made smaller when using copper, bronze, zinc or aluminum for the outside tubular shell. It is within the contemplation of my invention to modify the shape of the corrugations or grooves without essentially departing from the angle construction hereinabove described. The yielding springs 13 are 50 loosely mounted in the frames 1 but are prevented from losing out by reason of the hook-shaped ends which engage in the apertures in the frame, as illustrated in Fig. 55 4 of the drawings. The handles may be fastened to the frame in any suitable manner as by welding or riveting them in place.

It is, of course, within the contemplation 60 of my invention to utilize any desired common or special barrel bolts, pivot hangers, turn buckles, fasteners, hinges and catches, 65 to make these frames fit and operate prop-

erly on various kinds of wood and metal sash windows, and for other uses, such as poster or picture frames.

What I claim is:—

1. In metal frames of the class described, 70 the combination of hollow metal outer frames, inner angle frames snugly fitting in the outer frames, the outer frames having longitudinal depressions to frictionally engage the angle frames, the outer frames having an approximately U-shaped recessed portion extending longitudinally of the frame and adapted to receive a portion of the wire screens, screen-securing elements seatable in the recessed portions to frictionally hold the wire screen in place, metal strips engageable over the screen securing elements and wire screen, said strips having a longitudinal depression to frictionally engage the wire screen, the outer metal corners of suitable size to and frictionally engageable over the corners of the frames, and springs attached to one side of the metal frames to resiliently and frictionally hold the screens in place in channel guides on the windows. 80 85 90

2. In metal frames of the class described, 95 the combination of hollow metal outer frames, inner angle frames snugly fitting in the outer frames, the outer frames having longitudinal depressions to frictionally engage the angle frames, the outer frames having an approximately U-shaped recessed portion extending longitudinally of the frame and adapted to receive a portion of the wire screens, screen securing elements seatable in the recessed portions to frictionally hold the wire screen in place, metal strips engageable over the screen securing elements and wire screen, said strips having a longitudinal depression to frictionally engage the wire screen, hollow metal corners of suitable size to and frictionally engageable over the corners of the frames. 100 105 110

3. In metal frames of the class described, 115 the combinations of hollow metal outer frames, inner angle frames fitting in the outer frames, the outer frames having longitudinal depressions to frictionally engage the angle frames, the outer frames also having an approximately U-shaped recessed portion extending longitudinally of the frame and adapted to receive a portion of the wire screens, screen-securing means seatable in the recessed portions to fasten the wire screen in place, and metal strips engageable over the screen securing elements and screen wire, said strips having a longitudinal depression to frictionally engage the wire screen. 120 125

4. In metal screen window frames, the 130 combination of hollow metal outer frames, angle frames fitting in the outer frames, the outer frames having an approximately U-shaped recessed portion extending longitudinally of the frame and adapted to receive

a portion of the wire screens, screen securing means seatable in the recessed portions to hold the wire screen in place, metal strips engageable over the screen securing elements and screen wire, said strips having a longitudinal depression to frictionally engage the wire screen, hollow metal corners of suitable size to frictionally engage over the corner of the frames, and springs attached to one side of the metal frames to resiliently hold the screens in place in the windows. 10

JAMES H. BOST.
